US00D925164S

(12) **United States Design Patent** (10) Patent No.: **US D925,164 S**
Gilmour et al. (45) Date of Patent: **** Jul. 20, 2021**

(54) **CONFECTIONERY PRODUCT**

- (71) Applicant: **CANOPY GROWTH CORPORATION**, Ontario (CA)
- (72) Inventors: **Andrew Gilmour**, Almonte (CA); **Greg Aitken**, Smiths Falls (CA); **Elizabeth Nichols**, Smiths Falls (CA)
- (73) Assignee: **Canopy Growth Corporation**, Ontario (CA)
- (**) Term: **15 Years**
- (21) Appl. No.: **29/780,363**
- (22) Filed: **Apr. 23, 2021**
